PORTABLE GARMENT DRIERS
 Toni Olga Muench, 412 Washington St.,
 East Liverpool, Ohio
 Filed Aug. 4, 1959, Ser. No. 831,640
 1 Claim. (Cl. 211—86)

This invention relates to portable garment driers used particularly for drying woolen and knitted garments.

It is an object of the invention to provide a garment drier which is readily rolled for shipping or traveling when not in use and readily unrolled and suspended between two chairs or other suitable supporting fixtures when it is desired to dry garments.

It is another object of the invention to vary the size of the drying area.

Other objects and advantages of the invention will be set forth in the detailed description.

In the drawing accompanying and forming a part of this application:

FIGURE 1 is a plan view of the garment drier supported by suitable means in its fully extended condition to support its full complement of garments;

FIGURE 2 is a plan view showing the drier folded to support less than its full complement of garments;

FIGURE 3 is a sectional view, on an enlarged scale, taken on the line 3—3 of FIGURE 1 looking in the direction of the arrows to show a connection between the drier proper and its suspension means;

FIGURE 4 is a sectional view, on an enlarged scale, taken on the line 4—4 of FIGURE 2 looking in the direction of the arrows and showing the connection shown in FIGURE 3; and

FIGURE 5 is a fragmentary view, on an enlarged scale, of the connection shown in FIGURE 3.

The embodiment of the invention comprises a rectangular piece of meshed fabric, such as lace, as shown at 6, having finished or hemmed side edges 7 and the opposite ends folded upon themselves and sewed, as at 8 in FIGURE 5, to form a hem 9 at each end of the piece of meshed fabric.

A pair of tubular members 10 are inserted in each hem 9 and the length of each tubular member 10 is less than half the width of the meshed fabric 6, so that the adjacent ends of the tubular members 10 of each pair are spaced apart, as shown at 11 in FIGURE 1. The spacing of the tubular members 10 of each pair of members permits the folding of the meshed fabric 6 in half to de-

2

crease the amount of drying surface, as shown in FIGURE 2.

The meshed fabric 6 is suspended to extend in a horizontal plane in its fully extended or single ply condition or in its folded or two ply condition by two pairs of flexible members 12, such as cords. Each cord is extended through a tubular member 10 and a space in the meshed fabric, as shown at 13, and subsequently the ends of said cord are connected together to form a loop, as shown in FIGURES 1 and 2. When the meshed fabric is suspended in its fully extended or single ply condition, as shown in FIGURE 1, each loop 12 is engaged with a suitable supporting fixture or fixtures, such as a pair of hooks 14 secured in a wall or the backs of a pair of chairs 15, so that the meshed fabric 6 will be stretched in a horizontal plane.

When the meshed fabric 6 is in folded or two ply condition, as shown in FIGURE 2, the pair of loops at each opposite end of the fabric are engaged with the same supporting fixture or fixtures.

When the drier is not in use, the meshed fabric 6 is folded in half, the cords 12 are placed on the uppermost fold and the meshed fabric 6 is rolled to form a roll of not more than two and one-half inches.

Having thus described my invention, I claim:

A garment drier comprising a substantially rectangular meshed fabric having hems at opposite ends, a pair of axially spaced tubular reinforcing members in each hem, each of said tubular reinforcing members being substantially half the width of its related ends, a loop of flexible suspension material extending through each reinforcing member, each loop of flexible suspension material extending out of a tubular member at the edge of the fabric and from between the tubular members in the space therebetween, said fabric being foldable on a line between the pairs of loops at either end thereof.
